UNITED STATES PATENT OFFICE

ALBERT MORIN, OF ASNIÈRES, FRANCE.

CONSTRUCTION OF LIGHT-WEIGHT ENGINES.

1,314,352.

Specification of Letters Patent. Patented Aug. 26,

Application filed April 9, 1917. Serial No. 160,883.

To all whom it may concern:

Be it known that I, ALBERT MORIN, a citizen of the Republic of France, residing at 81 Rue du Ménil, Asnières, Seine, in the Republic of France, have invented new and useful Improvements in the Construction of Light-Weight Engines, of which the following is a specification.

The object of this invention is improvements in the construction of light weight engines, and such improvements consist essentially in making the cylinder of steel, the water jacket of aluminium and the combustion chamber of cast iron, these three pieces being assembled so as to obtain perfectly tight joints throughout and also to avoid any contact between the combustible gas and the aluminium water jacket. By the use of this method, engines of very light weight can be obtained, without being subject to the drawbacks due to the low strength of the aluminium and to the fact that it is easily attacked by the combustion gases.

The accompanying drawing is a vertical section exemplifying a constructional form of an engine cylinder according to the present invention. It will be observed that the cylinder *a* which is of steel is provided with a flange *b* upon which is placed the aluminium water jacket *c* surrounding the cylinder. This cylinder *a* is threaded at the upper part and is screwed into the cast iron cylinder head *d*, and this assures at the same time a perfect contact between the bottom surface of the cylinder head with the top surface of the water jacket, and of the bottom surface of the water jacket with the cylinder flange *b*.

A still greater tightness can be obtained by slightly heating the cylinder *a* before assembling and by dipping the screw thread part *e* in *sal ammoniac*. When assembled, the screw threads undergo a chemical attack which produces a hermetically tight joint between the cylinder and the head and a close adhesion, and on the other hand the contraction of the cylinder in cooling acts to press the water jacket tightly between the flange and the cylinder head.

It is evident that the present invention is not strictly limited to the above described disposition, and the various parts which make up the present device can be modified

as to shape, relative size and details resembling.

Having now described my invention I claim as new and desire to secure Letters Patent is:

1. In an internal combustion engine combination of a head piece, comprising a combustion chamber and the associated parts, for each cylinder, a threaded portion at the lower part said head piece for each combustion chamber, a cylinder provided with a screw and adapted to be screwed to each screw threaded portion, a projecting part of the head piece coming on the outside of each cylinder when in position, a part adapted to surround each cylinder a certain amount of clearance, and having at one end adapted to contact with a projecting portion of the head piece a step upon each of the cylinders adapted to come into contact with and grip the other end of the jacket when the cylinder is in position, all substantially as described.

2. A cylinder for light weight engine comprising in combination, a steel jacket, a flange cast with the jacket and surrounding the same, an aluminium jacket surrounding said inner jacket maintained upon said flange, and a cast iron cylinder head secured upon the top of the steel inner jacket and pressing upon aluminium water jacket; substantially as described and for the purpose set forth.

3. A cylinder for light weight engine having in combination, a steel inner jacket provided at the top with an exterior thread, a flange cast with the jacket and surrounding the same, an aluminium jacket surrounding said inner jacket maintained upon said flange, and a cast iron cylinder head screwed upon the top of the steel inner jacket and pressing upon aluminium water jacket; substantially as described and for the purpose set forth.

In testimony whereof I have signed my name to this specification in the presence of two subscribing witnesses.

ALBERT MORIN
